UNITED STATES PATENT OFFICE.

MILTON E. KREIDLER, OF BETHLEHEM, PENNSYLVANIA.

SHOE LAST.

1,410,324.

Specification of Letters Patent. Patented Mar. 21, 1922.

Application filed December 20, 1919, Serial No. 346,256. Renewed July 11, 1921. Serial No. 483,947.

To all whom it may concern:

Be it known that I, MILTON E. KREIDLER, a citizen of the United States, residing at Bethlehem, in the county of Northampton and State of Pennsylvania, have invented 5 new and useful Improvements in Shoe Lasts, of which the following is a specification.

This invention relates to improvements in shoe lasts and the principal object of the invention is to provide means for adjusting the last within the shoe so as to hold the shoe 10 in its original shape or to enlarge portions of the shoe to accommodate corns, bunions and other defects of the feet.

15 In carrying out my invention I provide means for adjusting the last longitudinally and other means for moving a part on the last vertically to stretch the toe part of the upper of the shoe.

20 The invention also consists in certain other features of construction and in the combination and arrangement of the several parts, to be hereinafter fully described, illustrated in the accompanying drawings and specifically pointed out in the appended claim.

25 In describing my invention in detail, reference will be had to the accompanying drawings wherein like characters denote like or corresponding parts throughout the several views, and in which:—

Figure 1 is an elevation of the last constructed in accordance with my invention and showing the same expanded.

30 Figure 2 is a longitudinal section showing the last contracted.

Figure 3 is a plan view.

Figure 4 is a horizontal section.

Figure 5 is a section on line 5—5 of Figure 2.

40 Figure 6 is a like section but showing the parts in a different position.

Figure 7 is a section on line 7—7 of Figure 1.

Figure 8 is a longitudinal section through 45 the gear supporting brackets.

Figure 9 is a sectional view through one of the worm gears.

Figure 10 is a view of the wrench for use with the device.

50 In these views 1 indicates the heel part of the last and 2 the toe part. These parts overlap each other, as shown, and the overlapping part of the toe portion is provided with a groove 3 for receiving the wrench 5 engaging end 4 of the rotatable shaft 5 carried by the heel part. The heel part is

provided with an angle bracket 6 which carries said shaft. The vertical part of this bracket carries a screw-threaded shaft 7 and the two shafts are geared together by the 60 bevel gears 8. A plate 9 is secured to the lower vertical face of the toe part 2 and this plate is provided with a screw threaded socket 10 for receiving the shaft 7. The bracket 6 also carries a guiding part 11 65 which engages an opening in the plate 9 for guiding the two parts of the last in their movements.

It will thus be seen that when the shaft 5 is rotated, by means of the wrench 12 70 shown in Figure 10, the screw threaded shaft 7 will also be rotated and the engagement of its threads with the screw threaded socket 10 will cause the two parts of the last to be moved relative to each other and thus the 75 last may be expanded or contracted in the shoe. The slot 3 in the overlapping part of the portion 2 will permit this overlapping part to pass by the end 4 of the shaft so that the two parts of the last may be brought 80 together. This slot is large enough to permit the entrance of the wrench.

A bow-shaped plate 13 is carried by the toe part 2 of the last and this plate embraces the upper portion thereof adjacent the toe. 85 This plate is vertically movable so that it may be used for stretching the upper of the shoe and in order to move this plate I provide the same with a pair of screw threaded studs 14 which project downwardly from its 90 inner wall. These studs engage the screw threaded hubs 15 of the gear wheels 16 and these gear wheels are carried by the U-shaped end of a plate 17, which is secured in a recess 18 formed in the part 2 of the last. 95 The looped end of the plate is provided with the openings 19 for receiving the hubs of the gears so that the said gears are rotatably held between the two parts of the plate with the screw threaded studs passing through 100 said hubs as clearly shown in Figures 2, 5 and 6.

The gears 16 are engaged by the last gear of a train of gears 20, carried by the plate and this train of gearing is set in motion by 105 the wrench 12 engaged by the square shank 21 of the shaft 22, rotatably mounted in the plate and carrying one of the gears. I prefer to offset the inner end of the plate and to place the first two gears on this offset portion so that these two gears are above the 110 plane of the other gears with the second and

third gears carried by the same shaft. By this means the shank 21 is placed nearer the top of the last so that it may be easily engaged with the wrench.

5 It will be seen that when the shaft 22 is rotated by the wrench its motion will be imparted to the two gears 16 and thus the studs 14 will be moved vertically to raise or lower the curved plate 13.

10 I may secure button-shaped members 23 to the outer face of said plate wherever desired to stretch the shoe at these points in order to form recesses in the shoe to receive the corns or other growths on the foot.

15 By my invention the last after being placed in the shoe may be expanded to stretch the same and to provide recesses to receive corns and the like. By the use of my device the shoes may be made to last longer 20 as wrinkles and creases can be stretched out of the shoe and the shoe may be made to assume its original shape after becoming wet.

It is thought from the foregoing description that the advantages and novel features 25 of my invention will be readily apparent.

I desire it to be understood that I may make changes in the construction and in the combination and arrangement of the several parts, provided that such changes fall within the scope of the appended claim. 30

What I claim is:—

A shoe last having a recess therein, a plate located in the recess and having its toe end of U-shape, a toothed wheel having a screw threaded central opening located between the 35 limbs of the U-shaped part of the plate, a toe plate, a screw threaded stud carried thereby and projecting into the recess and passing through the screw threaded opening in the toothed wheel, a train of gearing carried by the first mentioned plate, one of which meshes with the toothed wheel, and a squared shaft connected with the last gear of the train and constructed and arranged to receive a wrench to rotate the train of 40 gearing and the toothed wheel to move the 45 toe plate vertically.

In testimony whereof I affix my signature.

MILTON E. KREIDLER.
